(57) **CLAIM**

The ornamental design for a structure for displaying candle holders, as shown and described.

DESCRIPTION

FIG. 1 is a perspective view of a structure for displaying candle holders showing our new design;

FIG. 2 is a front view thereof, the rear view being identical; FIG. 3 is a left side view thereof, the right side view being identical;

FIG. 4 is a perspective view of a second embodiment showing our new design;

FIG. 5 is a front view thereof, the rear view being identical; and,

FIG. 6 is a left side view thereof, the right side view being identical.
